GEORGE C. VENNUM, OF WILMINGTON, DELAWARE, ASSIGNOR TO DIAMOND POWER
SPECIALTY CORPORATION, OF DETROIT, MICHIGAN, A CORPORATION OF MICHIGAN

BOILER CLEANER

Original application filed July 29, 1921, Serial No. 488,454. Divided and this application filed April 10, 1929. Serial No. 354,076.

This invention relates to boiler cleaners and has particular reference to a cleaner of the type in which a tubular member is provided with a plurality of discharge nozzles 5 for discharging jets of cleaning fluid adjacent the parts of the boiler to be cleaned.

An object of this invention is to provide a construction of this character in which the tubular member is mounted for movement 10 relative to the source of cleaning fluid supply and relative to its actuating means to compensate for variations in the position of the member due to warping or the like.

In particular, the present invention contemplates the provision of a flexible connection permitting an independent movement of the cleaner tube and contemplates the provision of a connection of this character, which will be simple in construction and yet thoroughly efficient in operation.

This application is a division of my pending application, Serial Number 488,454, filed July 29, 1921.

Other objects and advantages of this invention will become more apparent as the following description proceeds, particularly when reference is had to the accompanying drawings, wherein

Figure 1 is a semi-diagrammatic fragmentary sectional view through a steam boiler showing a cleaner constructed in accordance with the teachings of this invention applied to the same;

Figure 2 is an elevational view of a portion of the cleaner shown in Figure 1;

Figure 3 is a vertical sectional view taken through the cleaner shown in Figure 2;

Figure 4 is a sectional view taken substantially on the line 4-4 of Figure 3;

Figure 5 is a sectional view taken substantially on the line 5-5 of Figure 3 illustrating the valve in open position and

Figure 6 is a view similar to Figure 5 showing the valve in closed position.

Referring now particularly to the drawings wherein like reference characters designate corresponding parts throughout all views, there is illustrated in Figure 1 a boiler 10 having the wall 11 and the tubes 12. Projecting through an opening 13 in the wall 11

is a tubular blower element or pipe 14, provided with a series of discharge nozzles 15 adapted to direct jets of cleaning fluid adjacent the parts of the boiler to be cleaned. Externally of the wall 11, the blower element 55 is provided with a junction box or head 20, in which is contained mechanism for oscillating or rotating the blower element and through a portion of which cleaning fluid is supplied to the element.

The mechanism for actuating the blower element includes a tube 22 which extends through, and is journaled in bearings in the rear wall of the head and in a vertical partition 24 within this head. The tube 22 is connected with the element through a flexible coupling 26 which comprises a flexible sleeve having a flange on one end which is clamped between a flange 28 formed on the rear end of the tube 22 and a clamping collar 30 which is secured to the flange 28 by bolts 32. The other end of the flexible sleeve is provided with a flange that is clamped between a flanged collar 34 secured on the cleaner element, and a clamping collar 36 which is secured to the flange collar 34 by bolts 38.

This flexible coupling forms a substantially universal connection between the rigidly mounted head and the blower element and between the blower element and the blower element actuating means arranged within the head, thus it permits the blower element to be displaced slightly out of alignment with the tube 22 and allows the tube to be adjusted circumferentially by loosening the clamping bolts 38, to vary the direction in which the line of discharge nozzles are normally directed.

The mechanism for oscillating the cleaner element comprises a gear 40, which is secured on the tube 22 adjacent the inner side of the rear wall of the junction box. This gear engages a pinion 42 journaled on a stud shaft 44 secured to the rear wall of the junction box. The gear 40 and pinion 42 are adapted to be alternatively engaged by an internal gear segment 46, formed on a gear wheel 48, which is arranged eccentrically of the tube and 100

journaled on a collar or flange 50, projecting from the partition 24.

The internal gear segment 46 as shown, extends slightly less than half way around the gear wheel 48. With this construction it will be apparent that during one revolution of the gear wheel 48, the gear segment 46 will first engage the pinion 44 to rotate the gear element a part of one revolution in one direction and then disengage from the pinion 42 and engage the gear 40 to rotate the cleaner element a part of one revolution in the opposite direction to its initial position. Although the driving arrangement, as shown, effects an oscillation of the blower element, it will be readily apparent that the blower element might be mounted for continuous rotation in one direction if desired.

In the construction illustrated, however, the gear wheel 48 is driven through speed reducing gearing by an electric motor 52, mounted on the outside of the junction box. This gearing includes a pinion 54 carried by a shaft 56 which extends through and is journaled in bearings in opposite walls of the junction box. A gear 58 is secured to the forward end of the shaft 56, which gear engages a pinion 60 carried by a shaft 62 having one end journaled in a bearing in a wall of the junction box and its other end projecting through a bearing in a bracket 64. A worm wheel 66 is secured to the projecting end of the shaft 62 and engages a worm 68 carried by the shaft of the motor 52.

Cleaning fluid is supplied to the blower element 16 from a supply pipe 69, which opens into a chamber 70 formed in the head by the partition 24. A valve 72 is provided for controlling communication between the blower element 14 and the chamber 70, which valve closes communication between the element and the cleaning fluid supply pipe when the element is at rest and opens communication between the element and the pipe when the element is oscillated.

This valve is formed on the lower end of a depending lever 74, pivoted as at 76 on a segmental arm 78, formed on the forward end of the tube 22 having its upper end forked. When the cleaner element is at rest, the valve is held closed as shown in Figure 6 by the engagement of the forked end of the valve lever with a pin 80 projecting inwardly from the forward wall of the junction box. At the start, however, of an oscillating movement of the cleaner element, a prong 82 of the forked end of the valve lever by engagement with the stop pin 80, swings the lever in the direction to open the valve and the valve is held open by gravity during the remaining portion of the oscillating movement of the tube 22. This movement of the valve lever is limited by the engagement of the valve end thereof, with a stop pin 84 carried by the segmental arm 78.

Near the end of the return movement of the cleaner element, a prong 86 on the forked end of the valve lever 74 engages the pin 80 to swing the valve lever in a direction to close the valve, the valve again being held closed by the engagement of the forked end of the valve lever with the pin 80. The valve is held in close sliding engagement with the face of the segmental arm 78, which face constitutes a valve seat, by a flange 88 formed on the arm engaging the outer face of the valve. The valve is in the form of a disk and is of slightly greater diameter than the axial bore of the tube 22. It will be apparent that because of the difference in leverage between the forked end and the valve end of the valve lever 74, the valve will be opened and closed quickly so that there will be very little loss of steam, and yet because of the circular shape of the valve and valve opening, the start of the opening of the valve will be comparatively gradual which enables the steam to fill the cleaner element before the valve is opened wide, so that there is no danger of the admission of steam to the cleaner element causing injury to parts of the apparatus.

In operation, an oscillating movement is imparted to the blower element 14 by the gear 48 which is continuously rotated in one direction from the motor 52 by the pinion 54 and associated gearing. During oscillation of the blower element the valve 72 is opened and cleaning fluid is supplied to the element from the supply pipe 69 through the chamber 70 and the tube 22.

The flexible connection 26 permits a movement of the blower element relative to its rotating means and relative also to the head. This connection, therefore, compensates for the warping or expansion of the blower element from the heat of the boiler furnace and permits a movement of the blower element without causing a binding of the valve construction or a binding of the blower element itself within the head. Thus despite the movement of the blower element due to expansion or warping the positions of the tube 22 and valve 72 remain the same so that the mechanism functions efficiently regardless of displacement of the blower element.

The invention has, for the purpose of illustration, been described as a boiler cleaner adapted to clean parts of a boiler. It will be apparent, however, that the invention will find equal utility in cleaning any similar apparatus and it is to be therefore understood that the term "boiler" wherever used in the specification or claims is to be construed as meaning a heat transfer apparatus or fluid heater of any character, and the term "boiler cleaner" is to be construed as meaning a cleaner for any such apparatus.

While one embodiment of the inventive idea has been disclosed with considerable detail, it will be readily apparent that numer-

ous changes in the details of construction and arrangement of parts may be made without departing from the spirit of the invention. The right is therefore reserved to make such changes in the construction as will fall within the purview of the attached claims.

What I claim as my invention is:

1. In a boiler cleaner, the combination with a boiler wall and a blower pipe extending 10 transversely through said wall, said blower pipe being provided with a nozzle for discharging a cleaning fluid adjacent a surface to be cleaned, of a blower head mounting the blower pipe, means for turning said blower 15 pipe about its longitudinal axis to direct the nozzle toward different portions of the boiler to be cleaned, and means affording a yielding connection between said blower pipe and said blower head, said last mentioned means including a flexible connecting member.

2. In a boiler cleaner, a blower head, a cleaner element, means for moving said element relative to the blower head, and a flexible corrugated connection between said element 25 and said head permitting relative universal movement.

3. In a boiler cleaner, a blower element, a blower head, a tubular member journaled in said head, means associated with said head 30 for moving said tubular member, and a yielding connection between said tubular member and said blower element.

4. In a boiler cleaner, a blower head, a tube journaled in said head, a cleaner element, and a connection between said tube and said cleaner element permitting relative movement of said tube and cleaner element in parallel planes.

40 5. In a boiler cleaner, the combination with a blower element projecting through an opening in a boiler wall for directing jets of cleaning fluid adjacent portions of the boiler to be cleaned, and a blower head mounted exteriorly of said boiler wall and having an axis normally aligned with the axis of said blower element for supplying cleaning fluid to the same, of a flexible connection between the blower element and the said blower head providing 45 for relative movement between the blower element and blower head to positions where the said axes are out of alignment with respect to each other.

6. In a boiler cleaner, the combination with 55 a blower element projecting through an opening in a boiler wall for directing jets of cleaning fluid adjacent portions of a boiler to be cleaned, and a blower head arranged exteriorly of the boiler wall for supplying cleaning fluid to the blower element, of means including a tubular member of flexible material for connecting the blower element to the said blower head, said tubular member providing a passage for the cleaning fluid and being 60 adapted to be distorted to provide for move-

ment of said blower element longitudinally relative to said blower head.

7. In a boiler cleaner, the combination with a blower element, a blower head for supplying cleaning fluid to said blower element, and means associated with said head for moving said blower element, of a flexible connection between said blower element and said blower head providing for substantially universal movement of said blower element with respect 70 to said blower head.

8. In a boiler cleaner, the combination with a rotatable blower element, a head for supplying cleaning fluid to said blower element, and means associated with said head for rotating said blower element, of means providing for substantially universal movement between said blower element and said blower head, said means including a flexible driving connection between said rotating means and 80 said blower element.

9. In a boiler cleaner, the combination with a rotatable blower element, and a blower head normally aligned with the blower element for supplying cleaning fluid to the same, of a flexible connection between said blower head and said blower element providing for disalignment of the axes of the blower element and the blower head and providing for longitudinal movement of said blower element with respect 90 to said blower head.

10. In a boiler cleaner, the combination with a rotatable blower element, and a member having an axis normally aligned with the axis of said blower element for rotating the same, of a flexible tubular member connecting said member to said blower element and providing for relative movement between said blower element and said member to positions where the said axes are out of alignment 100 with each other.

11. In a boiler cleaner, the combination with a movable blower element, and a member having an axis normally aligned with the axis of said blower element for moving the same, of a flexible tubular member providing a driving connection between said member and said blower element to provide for movement of the axis of said blower element out of alignment with the said axis of said member, said flexible tubular member being adapted to be distorted to provide for longitudinal movement of said blower element with respect 110 to said member.

12. In a boiler cleaner, a blower head, a tube journaled in said head, a cleaner element, and a flexible tubular member providing a connection between said tube and cleaner element, said flexible tubular member being adapted to be distorted to provide for longitudinal movement of said cleaner element with respect to said tube.

In testimony whereof I affix my signature.
